PROPELLER CONSTRUCTION

Theodor H. Troller, New Philadelphia, Ohio, assignor to La-Del Conveyor & Manufacturing Company, a corporation of Ohio

Application December 11, 1942, Serial No. 468,651

11 Claims. (Cl. 230—114)

My invention relates in general to variable pitch propellers and more particularly to the improvement of a rim and a fitted blade construction adapted to give improved operating characteristics.

An object of my invention is the provision of a variable pitch propeller having a rim with a cylindrical outer surface to which is rotatively mounted a fitted blade, wherein the outer cylindrical surface is provided with a recess to receive the base portion of the blade, the construction and shape of the recess and of the lower base portion of the blade being such to provide a close clearance therebetween to give improved operating characteristics.

Another object of my invention is the provision of a rim having a substantially circular outer surface upon which one or more fitted blades may be rotatively mounted to give a variable pitch angle to the blades and in which there is no opening or aperture extending through the rim in the region of the area surrounding the base portion of the blade.

Another object of my invention is the provision of utilizing a rim having a substantially cylindrical outer surface instead of a non-circular construction which would tend to create turbulences in the air stream.

Another object of my invention is the provision of a rim to which variable pitch propeller blades may be rotatively mounted wherein the rim has a smooth cylindrical outer surface to minimize the turbulences and the friction losses in the air stream.

Another object of my invention is the provision of providing a close clearance between the base portion of the blades of a variable pitch propeller and the rim to which the blades are rotatively mounted in order to minimize noises and other air disturbances.

Other objects and a fuller understanding of my invention may be had by referring to the following description and claims taken in conjunction with the accompanying drawings, in which:

Figure 1 illustrates a front elevational view of a variable pitch propeller embodying the features of my invention, a portion of the drawings being shown in cross-section to more clearly set forth the construction of the invention;

Figure 2 is an enlarged view taken along the line 2—2 of Figure 1 and showing principally the recess in the outer cylindrical surface of the rim and a cross-section of the base portion of a blade which is arranged to fit in the recess;

Figure 3 is a cross-sectional view taken along

the line 3—3 of Figure 2 and shows the close clearance which exists between the bottom or base portion of the blade and the bottom of the recess;

5 Figures 4, 5 and 6 are views similar to Figure 3, the figures being taken respectively along the lines 4—4, 5—5, and 6—6 of Figure 2;

10 Figures 7 and 8 are cross-sectional views taken respectively along the lines 7—7 and 8—8 of Figure 2, the figures being shown in a matched relationship in order to show the depth of the recess on the side edge which has the greater pitch angle with respect to a plane passing through the zero pitch angle; and

15 Figures 9 and 10 are views taken, respectively, along the lines 9—9 and 10—10 of Figure 2, and showing respectively the depth of the recess along the side edge which has the smaller pitch angle with respect to a plane passing through the zero pitch angle.

20 With reference to Figure 1, my invention may be embodied in a variable pitch propeller comprising a plurality of blades 15 rotatively mounted at spaced intervals to a rim 17 which may be driven by any suitable type of motive power. The blades may be rotatively mounted to the rim by means of shanks 18 which rotatively fit in sockets in the rim 17. The inner end of the shank 18 may be actuated by a crank arm 19 to vary the 25 pitch angle of the blades. As illustrated, the crank arm 19 may be jointly operated by an axially movable control member or spider 20 actuated by a control lever 21 which extends transversely of an air flow passage 16 in which the propeller revolves. The lower end of the control lever 21 may be anchored to the bottom of the air flow passage 16 by means of a hinged connection 23 and the upper end of the control lever 21 is arranged to extend externally of the air flow 30 passage 16 so that as the control lever 21 is actuated back and forth the pitch of the propeller blades is accordingly varied. The forward end of the rim 17 is provided with a nose-like cover 24 and an axially movable control rod extends 35 through the forward portion of the nose-like cover and inter-connects the control member 20 to the intermediate portion of the control lever 21 at the hinged connection 22. The control mechanism for rotating the blades to vary the 40 pitch thereof may be the same as that shown and described in an application executed concurrently herewith in the name of Thomas O. Adams, Jr. and Theodor H. Troller for an application entitled improvement in Adjustable pitch propeller mechanism and assigned to the assignee 45 of this application. While I have illustrated a

50

55

particular type of control, it is to be clearly understood that the control may be of any suitable type and further that I do not want to be bound by the type of control shown herein for illustrative purposes. Each of the propeller blades 15 has a leading base portion 25 and a trailing base portion 26 which extend in substantially opposite directions from the axis of the shanks about which the blades are arranged to be rotatively adjusted to vary the pitch thereof within predetermined limits.

The leading base portion 25 is arranged to fit into a leading recess 27 provided in the outer cylindrical surface of the rim 17 and the trailing base portion 26 of the blade is arranged to fit in a trailing recess 28 mounted in the outer cylindrical surface of the rim 17. The leading and trailing recesses 27 and 28 are wide enough to allow the blade to be rotated to its predetermined limit of variable pitch angle. The leading recess 27 is provided with two side edges 29 and 30 and an end edge 31. The bottom of the leading recess 27 is indicated by the reference character 32. The bottom surface 32 of the leading recess 27 is defined by the rotation of a generatrix about the axis of the hub. The line 32 in Figures 7 and 9 which defines the bottom of the leading recess at the plane of the particular cross-section is the generatrix. Similarly, the trailing recess 28 is provided with side edges 33 and 34 and an end edge 35. The bottom of the trailing recess 28 is indicated by the reference character 36. The bottom surface 36 of the trailing recess 28 is defined by the rotation of a generatrix about the axis of the hub. The line 36 in Figures 8 and 10 which defines the bottom of the trailing recess at the plane of the particular cross-section is the generatrix. As illustrated in Figures 3 to 10, inclusive, the side edges 29 and 33 are deeper than the side edges 30 and 34. In other words, the side edge of the leading and trailing recesses 27 and 28 which has the greater pitch angle with respect to a plane passing through the zero pitch angle is deeper than the side edges which have the smaller pitch angle. The deeper side edges 29 and 33 and the end edges 31 and 35 are gradually sloped in order to prevent any abrupt change in the air flow as the air passes along the outer cylindrical surface of the rim 17 and into the leading and trailing recesses 27 and 28.

The bottom edge 40 of the leading base portion 25 and the bottom edge 41 of the trailing base portion 26 of the blades are shaped to substantially match the gradually sloped deeper side edges 29 and 33 of the leading and trailing recesses 27 and 28, see Figures 3 to 6, inclusive. As illustrated in Figures 2 and 6, the bottom edge 41 of the trailing base portion 26 is provided with an angularly disposed flange 42 which is arranged to match the deeper side edge 33 of the trailing recess 28. The bottom surfaces 32 and 36 of the leading and trailing recesses 27 and 28 are arcuate in a longitudinal direction, and the bottom edges 40 and 41, including the flange 42 of the blade 15, are correspondingly arcuate to provide a close clearance between the bottom of the fan and the bottom of the recesses. The recesses may be cast or otherwise suitably provided in the rim 17. In the event the recesses are cast in the rim 17, the patterns used for making the casting may have the recesses provided therein. In cutting the recesses in the patterns, the bottom surfaces thereof may be determined by placing a given blade having a given under

surface in the hole for the shank of the blade and rotating same between predetermined limits, so that the generatrix of the under surface of the blade serves as a measure for the depth of the recesses.

The width of the recesses is such to permit the blades to be rotated within a predetermined range of pitch angles, the greater pitch angle being shown in the cross-sectional view of Figure 2 and the smaller pitch angle being shown by the dash-dot line in Figure 2. In this invention, it is to be understood that the leading and trailing recesses 27 and 28 may have any angular position with respect to the zero pitch line depending upon the range through which the blade is to be adjustably moved to obtain the most desirable operating characteristics. In other words, the leading and trailing recesses 27 and 28 may be shifted in a clockwise direction to have a smaller angle with respect to the zero pitch line, or they may be shifted in a counter-clockwise direction to have a larger angle with respect to the zero pitch line.

In my invention, I have no hole or aperture extending through the rim in the region of the base portion of the fan blade. By eliminating the hole or aperture around the base portion of the blade, I am able to produce a variable pitch fan construction which has a minimum of noises and air disturbances. Also, in my invention I am able to employ a rim having an outer cylindrical smooth surface as distinguished from a non-circular rim or a rim utilizing a regular surface, such for example, having flat surfaces adjacent the lower edges of the blades.

The leading and the trailing recesses 27 and 28 may be cast in the outer cylindrical surface of the rim and inasmuch as there may be irregularities in the casting of the recesses, I provide the shallow edges 30 and 34. In other words, in a theoretical sense, assuming that the bottom of the recesses and the bottom edge of the blades were perfectly smooth and free of mechanical irregularities, then there would be no need for the shallow edges 30 and 34. Accordingly, the shallow edges 30 and 34 are made just deep enough to take care of mechanical irregularities in the casting or otherwise manufacturing of the recesses.

In operation of my invention, the air flows substantially uninterruptedly over the outer cylindrical surface of the rim 17 and produces an improved fan operation. The noise is reduced to a low minimum and in addition there is no mechanical concentration of stresses as is experienced in certain prior art devices which employ a fairing or other shell about the rim through which the fan blades extend such, for example, as apertures or openings provided in the fairing which allow for rotational movement of the blades to accommodate for settings of variable pitch angles.

My invention finds particular utility with reference to a blade having a relatively wide base which embraces a substantial distance around the rim or mounting to which it is rotatively connected. While I have shown the recesses 27 and 28 in a rim having an outer cylindrical surface, it is to be understood that my recesses 70 may be utilized in a rim or mounting having a spherical, convex, or other curved surface and in the claims the term "cylindrical outer surface" shall be interpreted to include spherical, convex and all types of curved surfaces as well as cylindrical surfaces.

Although I have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

I claim as my invention:

1. In a variable pitch propeller mechanism, the improvement of a rim and a fitted blade construction, said rim having substantially a cylindrical outer surface, said blade being rotatively mounted about an outwardly extending axis in the rim for adjusting the blade pitch within predetermined limits and having a leading base portion and a trailing base portion extending in substantially opposite directions from said axis, said outer surface of the rim having a leading recess extending forwardly from said axis to receive the leading base portion of the blade and having a trailing recess extending rearwardly from said axis to receive the trailing base portion of the blade, the bottom surfaces of said recesses being portions of surfaces of revolution, the axes thereof being the first mentioned axis, each surface of revolution having a generatrix defining a line with a curvature close to the curvature of the rim, the under surface of said leading base portion and of said trailing base portion being substantially congruent and coaxial with the bottom surfaces of the leading and trailing recesses respectively.

2. In a variable pitch propeller mechanism, the improvement of a rim and a fitted blade construction, said rim having substantially a cylindrical outer surface, said blade being mounted on the rim and extending therefrom and being rotatable about an axis for adjusting the blade pitch within predetermined limits and having a leading base portion and a trailing base portion extending in substantially opposite directions from said axis, said outer surface of the rim having a leading recess extending forwardly from said axis to receive the leading base portion of the blade and having a trailing recess extending rearwardly from said axis to receive the trailing base portion of the blade, the bottom surfaces of said recesses being portions of surfaces of revolution, the axes thereof being the first mentioned axis, each surface of revolution having a generatrix defining a line with a curvature close to the curvature of the rim, the under surface of said leading base portion and of said trailing base portion being substantially congruent and coaxial with the bottom surfaces of the leading and trailing recesses respectively.

3. In a variable pitch propeller mechanism, the improvement of a rim and a fitted blade construction, said rim having substantially a cylindrical outer surface, said blade being mounted on the rim and extending therefrom and being rotatable about an axis for adjusting the blade pitch within predetermined limits and having a leading base portion and a trailing base portion extending in substantially opposite directions from said axis, said outer surface of the rim having a leading recess extending forwardly from said axis to receive the leading base portion of the blade and having a trailing recess extending rearwardly from said axis to receive the trailing base portion of the blade, the bottom surfaces of said recesses being portions of surfaces of revolution, the axes thereof being the first mentioned axis, each surface of revolution

having a generatrix defining a line with a curvature close to the curvature of the rim, the under surface of said leading base portion and of said trailing base portion being substantially congruent and coaxial with the bottom surfaces of the leading and trailing recesses respectively, each said recess having two side edges between which said blade is adjustably moved to vary the pitch thereof, the side edge which has the greater pitch angle with respect to a plane passing through the zero pitch angle being deeper than the other side edge.

4. In a variable pitch propeller mechanism, the improvement of a rim and a fitted blade construction, said rim having substantially a cylindrical outer surface, said blade being mounted on the rim and extending therefrom and being rotatable about an axis for adjusting the blade pitch within predetermined limits and having a leading base portion and a trailing base portion extending in substantially opposite directions from said axis, said outer surface of the rim having a leading recess extending forwardly from said axis to receive the leading base portion of the blade and having a trailing recess extending rearwardly from said axis to receive the trailing base portion of the blade, the bottom surfaces of said recesses being portions of surfaces of revolution, the axes thereof being the first mentioned axis, each surface of revolution having a generatrix defining a line with a curvature close to the curvature of the rim, the under surface of said leading base portion and of said trailing base portion being substantially congruent and coaxial with the bottom surfaces of the leading and trailing recesses respectively, each said recess having two side edges between which said blade is adjustably moved to vary the pitch thereof, the side edge which has the greater pitch angle with respect to a plane passing through the zero pitch angle being deeper than the other side edge, said deeper side edges of the recesses being gradually sloped to minimize air disturbances.

5. In a variable pitch propeller mechanism, the improvement of a rim and a fitted blade construction, said rim having substantially a cylindrical outer surface, said blade being mounted on the rim and extending therefrom and being rotatable about an axis for adjusting the blade pitch within predetermined limits and having a leading base portion and a trailing base portion extending in substantially opposite directions from said axis, said outer surface of the rim having a leading recess extending forwardly from said axis to receive the leading base portion of the blade and having a trailing recess extending rearwardly from said axis to receive the trailing base portion of the blade, the bottom surfaces of said recesses being portions of surfaces of revolution, the axes thereof being the first mentioned axis, each surface of revolution having a generatrix defining a line with a curvature close to the curvature of the rim, the under surface of the said leading base portion and of said trailing base portion being substantially congruent and coaxial with the bottom surfaces of the leading and trailing recesses respectively, each said recess having two side edges between which said blade is adjustably moved to vary the pitch thereof, the side edge which has the greater pitch angle with respect to a plane passing through the zero pitch angle being deeper than the other side edge, each said recess also having an end edge, said end edges and said

deeper side edges of the recesses being gradually sloped to minimize air disturbances.

6. In a variable pitch propeller mechanism, the improvement of a rim and a fitted blade construction, said rim having substantially a cylindrical outer surface, said blade being mounted on the rim and extending therefrom and being rotatable about an axis for adjusting the blade pitch within predetermined limits and having a base portion extending from said axis, said rim having a recess in the outer surface thereof, the bottom of the base portion of the blade fitting in the said recess, the bottom surface of said recess being a portion of a spherical surface of revolution, the axis thereof coinciding with the first mentioned axis, said spherical surface of revolution having a generatrix defining a line, said line intersecting said axis at a point spaced at a distance from the center of rotation of the rim substantially equal to the radius of the rim, the bottom surface of said base portion being substantially congruent with the bottom surface of the recess, said recess having two side edges between which said blade is adjustably moved to vary the pitch thereof.

7. In a variable pitch propeller mechanism, the improvement of a rim and a fitted blade construction, said rim having substantially a cylindrical outer surface, said blade being mounted on the rim and extending therefrom and being rotatable about an axis for adjusting the blade pitch within predetermined limits and having a leading base portion and a trailing base portion extending in substantially opposite directions from said axis, said outer surface of the rim having a leading recess extending forwardly from said axis to receive the leading base portion of the blade and having a trailing recess extending rearwardly from said axis to receive the trailing base portion of the blade, the bottom surfaces of said recesses being portions of surfaces of revolution, the axes thereof being the first mentioned axis, each surface of revolution having a generatrix defining a line with a curvature close to the curvature of the rim, the under surface of said leading base portion and of said trailing base portion being substantially congruent and coaxial with the bottom surfaces of the leading and trailing recesses respectively, each said recess having two side edges between which said blade is adjustably moved to vary the pitch thereof, the side edge which has the greater pitch angle with respect to a plane passing through the zero pitch angle being deeper than the other side edge, said trailing base portion having an angularly disposed flange which substantially matches the side edge in the trailing recess which has the greater pitch angle.

8. In a variable pitch propeller mechanism, the improvement of a rim and a fitted blade construction, said rim having substantially a cylindrical outer surface, and a socket therein, said blade having a shank portion fitting in said socket and a base portion extending outwardly from the rim, said blade being rotatable about an axis for adjusting the blade pitch within predetermined limits, said rim having a recess in the outer surface thereof and extending from the edges of the socket, the bottom of the base portion fitting in the said recess, the bottom surface of said recess being a portion of a spherical surface of revolution, the axis thereof coinciding with the first mentioned axis, said spherical surface of revolution having a generatrix

defining a line, said line intersecting said axis at a point spaced at a distance from the center of rotation of the rim substantially equal to the radius of the rim, the bottom surface of said base portion being substantially congruent with the bottom surface of the recess, said recess having two side edges between which said blade is adjustably moved to vary the pitch thereof.

9. In a variable pitch propeller mechanism, 10 the improvement of a rim and a fitted blade construction, said rim having substantially a cylindrical outer surface, said blade being mounted on the rim and extending therefrom and being rotatable about an axis for adjusting the blade pitch within predetermined limits and having a base portion extending from said axis, said rim having a recess in the outer surface thereof, the bottom of the base portion of the blade fitting in the said recess, the bottom surface of said recess being a portion of a surface of revolution, the axes thereof being the first mentioned axis, the surface of revolution having a generatrix defining a line with a curvature close to the curvature of the rim, the under surface of said base portion being substantially congruent and coaxial with the bottom surface of the said recess.

10. In a variable pitch propeller mechanism, 30 the improvement of a rim and a fitted blade construction, said rim having substantially a cylindrical outer surface, said blade being mounted on the rim and extending therefrom and being rotatable about an axis for adjusting the blade pitch within predetermined limits and having a base portion extending from said axis, said rim having an auxiliary surface, said auxiliary surface being a portion of a surface of revolution, the axes thereof being the first mentioned axis, the surface of revolution having a generatrix defining a line with the curvature 40 close to the curvature of the rim, the under surface of said base portion of the blade being disposed close to and substantially congruent and coaxial with said auxiliary surface.

11. In a variable pitch propeller mechanism, 45 the improvement of a cylindrical rim and a fitted blade construction, said blade being mounted on the rim and extending therefrom and being rotatable about an axis for adjusting the blade pitch within predetermined limits and having a leading base portion and a trailing base portion extending in substantially opposite directions from said axis, said rim having a recess on its outer surface to receive the base portions of the blade, said recess comprising a leading recess 55 extending forwardly from said axis to receive the leading base portion of the blade and having a trailing recess extending rearwardly from said axis to receive the trailing base portion of the blade, the bottom surfaces of said recesses being portions of spherical surfaces of revolution, the axes thereof coinciding with the first mentioned axis, each spherical surface of revolution having a generatrix defining a line, each said line respectively intersecting said first mentioned axis at a point spaced at a distance from the center of rotation of the rim substantially equal to the radius of the rim, the bottom surface of said leading base portion and of said trailing base portion being substantially congruent with the bottom surfaces of the leading and trailing recesses respectively, each said recess having two side edges between which said blade is adjustably moved to vary the pitch thereof.
